UNITED STATES PATENT OFFICE.

GARRY J. DORMANDY, OF TROY, NEW YORK, ASSIGNOR TO UNITED SHIRT & COLLAR COMPANY, OF TROY, NEW YORK, A CORPORATION OF NEW YORK.

FOLDING-MACHINE.

No. 804,317.

Specification of Letters Patent.

Patented Nov. 17, 1908.

Application filed February 27, 1904. Serial No. 195,528.

To all whom it may concern:

Be it known that I, GARRY J. DORMANDY, a citizen of the United States, residing in Troy, county of Rensselaer, and State of New York, have invented certain new and useful Improvements in Folding-Machines, of which the following is a specification.

My invention relates to machines for infolding or inturning the edges of blanks for cuffs, collars or like articles; and more particularly to mechanisms and parts for effecting the folding and pressing of the folds of blanks intended to make up the two parts of a cuff or analogous article preparatory to sewing such parts together.

One of the principal objects of my invention is to produce a machine that will afford a more simple construction and operation and possess other advantages, and more particularly by employing pressure applying mechanism for bringing about a suitably powerful creasing pressure upon the folds of the blanks while the latter remain undisturbed upon the said support, but at a time when the folds are not engaged with the infolding mechanism, and preferably have also been freed from the templet or defining member over which the folds were formed.

Other objects will appear during the description hereinafter following.

I will first describe a folding machine embodying my invention, and then point out the novel features in the claims.

In the accompanying drawings; Figure 1 is a top view of the folding machine embodying my invention, the particular machine illustrated therein being one that is adapted for the infolding of blanks for cuffs having two square and two rounded corners. Fig. 2 is a vertical sectional view of said machine taken upon the plane 2—2 of Fig. 1. Fig. 3 is a sectional view similar to Fig. 2, but showing the parts in a different position or stage of operation.

Similar letters of reference are employed to designate corresponding parts in the several figures of the drawings.

In general the machine of the present application may be said to contemplate a bed which is designated by the character A, which serves as a support for the blanks during the folding and pressing operations hereinafter to be described; and in combination therewith suitable infolding instrumen-

talities or infolders; also a member for defining the folds to be produced upon the blanks upon the bed of the machine during the infolding operation; also a treadle or analogous pressure applying means by which a suitably powerful pressure such as has heretofore been found necessary to produce an efficient creasing of the folds, may be brought about. The machine illustrated also discloses means for heating the bed in a manner which is well known and has been found desirable, if not practically necessary, for the manufacture of blanks for all kinds of cuffs, collars and analogous articles. Such heating means in the present machine is provided in the hollow portion or chamber indicated at B in the bed of the machine directly beneath its middle portion, or the portion upon which the infolding of the blank is carried on. A convenient means of heating the bed is by supplying steam to the chamber B, but other means are equally available, such as the use of gas jets.

I have illustrated a species of folding mechanism which is not in itself made the subject of the present application, and therefore need not be described in great detail. It comprises a series of infolders which are suitably grouped or spaced around the middle of the bed on the machine, according to the form of the blanks to be infolded. These infolders are designated by the reference letters C C' C², which are fitted and connected with actuating mechanism so as to operate in the order named. A convenient form of infolder actuating mechanism is that shown in my prior patent No. 708,030, and generally speaking may be described as consisting in an oscillating ring D' having a handle D by which the operator may effect oscillations thereof; the said ring being fitted to an annular slide-way formed in the bed of the machine. Cams E E' E² constitute the operative connections between said oscillating ring D' and the infolders C C' C², and as will be seen each of said cams is provided with eccentric and concentric portions, which are timed to operate in sequence, the eccentric portion of cam E first coming into operation, succeeded by that of cam E', and lastly by that of cam E². The above described infolding mechanism is merely one convenient means for producing movements inward and outward relatively between the

infolders and the blanks, which are to be folded upon the support.

The die or templet contemplated in the present invention may be any wellknown form of templet, but for convenience is illustrated as being a templet of the species heretofore termed an expanding and contracting templet; that is, one which is provided with inwardly and outwardly moving parts 10 having edge portions constructed and fitted to contact directly with the blanks upon the bed or support in order to define the folds thereof. This species of templet is most desirable for carrying out the manufacture of 15 cuffs such as that which the machine illustrated herein is adapted to infold, and for all forms of blanks in which all the sides are to be folded in one operation.

In Fig. 1 herein it will be seen that the 20 said templet or fold-defining member comprises a body or stock portion F, at the bottom of which are secured plates f. The purpose of these plates is to rest upon the blanks to be infolded for the purpose of defining or 25 outlining the shape of the folds; and they are, therefore, made comparatively thin or even sharp so that when the extended edges of the blanks are inturned or infolded over the edge of the templet plates a substantially 30 accurate fold will be formed. For effecting an inward and outward movement of the templet plates f, I have provided diagonally arranged slide-ways in the templet body portion or stock F. The templet plates 35 are connected to slides which are adapted to move backward and forward in these diagonal slide-ways; and for convenience, all of the same diagonally moving slides are operated through link connections, the ends of 40 the links being connected to the respective slides and to a central member which may conveniently be actuated through an oscillating handle G. This handle G should extend forwardly and may conveniently be employed by the operator for effecting the 45 hereinafter described upward and downward movements of the templet as well as the expanding and contracting operations just described. A convenient way to fit the said 50 templet to be positioned upon and removed from the blanks is shown herein in a templet supporting arm H, which extends rearwardly to pivotal parts h h, and is extended still further rearwardly to the counterbalance weight H'. For reasons which will 55 hereinafter appear, the arm H is made to diverge toward the pivotal points thereof.

I will now describe a novel pressure applying mechanism, whose purpose is to effect 60 or bring about a suitably powerful creasing pressure upon the folds of the blanks, while the folds remain undisturbed upon the bed or support, but subsequently to the relative outward movement of the infolders; and 65 also preferably subsequently to the with-

drawal of the fold-defining edges of the templet, by contraction or otherwise, from the interior of the folds.

It is particularly important herein that the pressure applying mechanism should 70 take effect after the infolders are moved to their outward position, and while the same are disengaged from the folds of the blank. It will be clear that such operation relieves the infolders from the necessity of taking 75 part in the final pressing operation upon the folds of the blank, and other advantages might be pointed out. By relieving the infolders from taking part in the pressing, said infolders are enabled to be constructed, 80 in their thin edge portions, of such thinness of metal and of such width of the thin portions, as to render them of maximum efficiency in the folding inwards of the blank edges. 85

The pressure applying mechanism contemplated by my invention consists of a part such as a treadle, through which an operator may apply his muscular efforts to be transmitted to the fold of the blank, or some 90 equivalent part to take the place of a treadle when the machine is actuated by power. Intermediate connections are provided between the said pressure applying treadle and some member of the machine 95 which is capable of being positioned upon the folded blanks after the infolders have been withdrawn outwardly from above the fold; and also preferably after the fold-defining edges of the templet have been 100 withdrawn from beneath the folds.

My preferable construction is the employment of a member distinct from the templet, which member I have termed a presser. Said presser may conveniently consist in a 105 flat plate or block, which is of substantially the size of and co-extensive with the infolded blanks, but it is obviously only necessary that the presser shall be of such form that it will contact with the folds in the 110 blanks, and therefore the central portion might be omitted. As is well known, blanks vary in outline, and blanks of given outline vary in size, and therefore the blank contacting surfaces of the presser should be 115 easily replaceable by one of different size or shape; or it may be otherwise adjustable in analogy to the adjustments for size of templets, as explained in prior patents, e. g., No. 666,766, of January 29, 1901. 120

J indicates my preferred form of presser. It consists in a horizontally arranged plate or block which is substantially the size and co-extensive with the infolded blanks. The presser J is normally in an inoperative position, which may for convenience be at the rear of the middle portion of the bed of the machine. This position is shown in Figs. 1 and 2. I have illustrated a mechanism for carrying the presser J from its inop- 125 130

erative position into a position directly above the infolded blanks. The mechanism so illustrated comprises a presser carrying arm K, to which the presser J is secured in any suitable manner, and the arm K extends rearwardly to a sliding pivot consisting of a roller L turning about a pin fixed in the frame of the machine, and longitudinal slots formed in the rearward extensions K' of the presser carrying arm K. The purpose of the sliding pivot will be clearly understood to be to permit the presser J to be shifted from its normal position, shown in Figs. 1 and 2, to its operative position, shown in Fig. 3. An adjusting screw l may for convenience be employed in each of the longitudinal slots of the extensions K' for insuring accuracy.

I have stated that a treadle is employed in the present instance for bringing about the application of pressure to the folds of the blank. I have shown what may be termed a double treadle. This consists in substantially two treadles. The upper treadle M is directly above the lower treadle N, so that when the former is depressed by the foot of the operator, or in other manner, it will eventually contact and engage with the said treadle N, so that the continued movement will carry both treadles downward.

The treadle M is shown as connected by means of a flexible member such as a cord, rope or chain M', with an extension k of the presser carrying arm K, in such manner that a depression of the treadle M will cause a tension in the flexible member M', which will serve to move forwardly the presser carrying arm K. A spring m is interposed in such flexible connection M', in order to prevent breakage when the same has reached its limit of movement as defined by the movement of the presser carrying arm K.

The arm K is fitted with means to effect an upward and then a downward movement therein simultaneously with its forward movement effected through the treadle N. Such means may conveniently comprise a cam consisting of a cam roller P, provided on the presser carrying arm K and a fixed cam p, having an upwardly inclined surface to effect the elevation of the presser carrying arm K during the first part of the forward movement, and a downwardly inclined surface for permitting a downward movement of the presser carrying arm and presser J at the forward end of the movement thereof. At the conclusion of the forward movement of the presser, it will as herein arranged rest upon the middle part of the bed of the machine or upon the blanks thereon, as shown in Fig. 3.

I have shown a hook engagement as a convenient means of temporarily connecting the treadle N with the member of the ma-

chine that is to be depressed upon the folds of the blanks to crease the same. I have, however, shown a preferable arrangement of providing said hook engagement intermediate of the treadle N and the arm K, carrying the presser J. Such hook engagement may be effected in a convenient manner as follows: The hook k' at the lower end of the downward projection k of the arm K will be carried from the position shown in Fig. 2 to the position shown in Fig. 3, when the presser J is moved from its normal or inoperative position to its forward or operative position.

The co-acting hook n' on the upper end of the arm n is fitted for upward and downward movements, which are effected by link N' and lever N² intermediate the arm n and the treadle N. A cam surface is provided at Q on the arm n, and this is intended to engage with a roller which turns about a fixed pivot at q, the effect of this arrangement being that the arm n is thrown rearwardly, causing the hook n' to engage the hook k' in the manner shown in Fig. 3, and immediately after the downward movement of the treadle N is begun. The continued downward movement of the treadle N to the extreme position shown in Fig. 3 will through the engagement of hooks n' k' effect a powerful depression or lowering of the presser J, which rests upon the folds of the blanks. The ratio of the leverages intermediate of the treadle N and the presser J is such as to cause a greatly multiplied pressure to be applied to the folds of the blanks. The treadle may be considered a presser-actuating member operated by foot, though obviously foot power need not always be used.

The support which holds the blanks and relatively to which the blanks are not moved during the operations upon it, should be stationary; at least, its location relatively to the general location of the infolders or to the framework of the machine should be substantially constant. In characterizing the support, however, in the claims as constant or stationary, it is not intended to exclude an unsubstantial vibration or other slight movement if employed. Nor where the support which holds the blanks is expressed in the claims as in a constant position relatively to the general position of the infolders, is it intended to exclude a joint movement together of the support and the infolders, as, for example, a bodily movement of the machine as a whole, if that should be desired; so long as the blank retains the same position relatively to the outward position of the infolders and to the support beneath it throughout the operations of the templet, the infolders and the presser.

An important feature of the described ma-

70

chine is that the infolders, which may have wide thin inner edges because not subject to the destructive repeated pressing actions, move outwardly beyond the blank edges, 5 and as so moved outwards, inclose a space which corresponds with the presser. The presser may pass entirely within said space because the infolders both at their thin portions and their stock portions are out of the 10 way of the presser. And the presser, because of having a proper form, not an indefinite flat member, but with edges that can clear the folders, passes within the latter after they are moved outwards and comes 15 down upon the folds, squeezing them against the support beneath. This action, moreover, is such that can take place immediately after the infolders leave the folds, so that the folds are only instantaneously, or not at all, 20 left to themselves. This is by reason of the explained construction of the infolders and presser, enabling the latter to almost come to pressing position as the infolders move outwardly, and assume pressing position 25 when the infolders are in outward position. The presser mechanism is such as to carry this action out. An important advantage lies in overcoming the tendency of a fold to open out if left unprotected before 30 being fixed by creasing pressure.

What I claim as my invention is:

1. A folding-machine comprising a support which holds the blanks during the infolding and pressing operations thereof, a 35 fold-defining member, mechanical means for accurately positioning said defining member upon the blanks upon said support, infolders having an outward position and an inward position, together with means for producing 40 inward and outward movements thereof whereby edges of the blanks are folded over edge portions of the defining member and whereby said infolders are subsequently moved outwardly from the folded edges of 45 the blanks; a presser member, and operative means which may be applied subsequently to the outward movement of said infolders for producing through said presser member a creasing pressure upon the folds of the 50 blanks while the latter still remain in the same place occupied by them during the folding operation, relatively to said support and to the general location of the infolders.

2. A folding machine comprising a bed 55 or support upon which the blanks to be infolded may be laid, a fold-defining member, mechanical means for accurately positioning said defining member upon the blanks upon said support, infolding mechanism and 60 means for producing a movement of said mechanism relative to the blank whereby an edge of the blank is folded upon an edge portion of the fold-defining member and whereby said mechanism is subsequently re- 65 moved from the folded edge of the blank;

means for withdrawing said fold-defining member from the folded edge of the blank, a presser member and operative means which may be applied subsequently to the withdrawal of said infolding mechanism and 70 of said fold-defining member, for producing through said presser member a creasing pressure upon the blanks while the latter still remain substantially in the same location occupied by them during the folding opera- 75

3. A folding machine comprising a rigid substantially stationary blank support, which bears the blanks during infolding, a contractile templet fitted to be accurately lowered upon the blank supporting surface of said support, a presser member, independent infolders, means for contracting said templet to withdraw it from the folds of a blank operated upon, means for withdrawing said infolders from their engagement with such folds, and subsequently operative means for applying through said presser member a creasing pressure upon such blank, both said withdrawing means and also said pressure 85 applying means being operative while such blank remains in substantially its original position on said support.

4. A folding machine comprising a substantially stationary blank support, a fold-defining member fitted to be lowered upon the blank supporting surface of said support, infolding mechanism and means for producing a movement thereof relative to the blank whereby an edge of the blank is 100 folded upon an edge portion of the fold-defining member and whereby said mechanism is subsequently removed from the folded edge of the blank, means for withdrawing said fold-defining member from the folded 105 edge of the blank, a laterally movable presser, and means operative subsequently to the withdrawal of said infolder and of said fold-defining member for forcing said presser upon the blank while it remains in substantially 110 its original position on said support.

5. A folding machine comprising a substantially stationary blank support, a contractile templet fitted to be accurately lowered upon the portion of said support on 115 which the blanks bear during infolding, independent infolders, means for contracting said templet to withdraw it from the folds of a blank operated upon, means for withdrawing said infolders from their engagement with such folds, a presser, and means operative subsequently to said withdrawing means for forcing said presser upon the blank while it remains in substantially 120 its original position on said support.

6. A folding machine comprising a substantially stationary blank support, a contractile templet fitted to be accurately lowered upon the portion of said support on 125 which the blanks bear during infolding, in-

- dependent infolders, means for withdrawing said infolders from engagement with the folds of a blank operated upon, means for contracting said templet and for withdrawing it from such folds, a presser member, and means for applying through said presser member a creasing pressure to such folds, all said means being operative in the order named and while such blank remains in substantially its original position upon said support.
7. A folding machine comprising a substantially stationary blank support, a contractible, templet fitted to be accurately lowered upon the portion of said support on which the blanks bear during infolding, independent infolders, a presser, means for withdrawing said infolders from engagement with the folds of a blank operated upon, means for contracting said templet and for withdrawing it from such folds, and means for forcing said presser upon such blank, all said means being operative in the order named and while such blank remains in substantially its original position upon said support.
8. A folding machine having in combination a fold-defining member, infolders, and a presser for pressing the folds of blanks, said presser being normally in inoperative position, a treadle, and operative connections between said presser and treadle, whereby upon the actuation of said treadle, said presser will be moved laterally toward an operative position and then depressed upon the folds of the blanks.
9. A folding machine having in combination a fold-defining member, infolders, means for withdrawing said fold-defining member and said infolders from their operative position, and a subsequently operative presser for pressing the folds of blanks, said presser being normally in inoperative position, a treadle, operative connections between said presser and treadle, whereby upon the actuation of said treadle, said presser will be automatically brought toward an operative position and then depressed directly upon the folds of the blanks, and heating means for said support.
10. In a machine for folding cuff blanks or analogous articles, the combination with blank defining and folding instrumentalities, of a presser independent of the blank defining and folding instrumentality, said presser connected with the machine to move toward the blanks on the support, and a power applying device comprising connections normally disengaged from said presser but automatically engageable therewith when operated, substantially as and for the purpose described.
11. In a machine for folding cuff blanks or the like, the combination with folding mechanism and a templet, or a presser inde-
- pendent of the folding mechanism and templet, independent positioning arms for the templet and presser, both pivoted a substantial distance toward the rear of the blank position, and power multiplying mechanism which is normally disengaged from the presser and is operable to become engaged with and to actuate said presser after the operations of and the withdrawal of the infolding mechanism and templet.
12. A folding machine comprising a blank support, fold-defining and fold-producing means disengageable from a blank on said support by a movement in the plane of said blank, a presser, and means operative subsequently to such disengagement for moving said presser first laterally, then downwardly, upon such blank.
13. In a folding machine, a blank support, folding devices, a presser, and a treadle operatively connected to said presser to move it first laterally over, then downwardly, upon said support.
14. A folding machine comprising a blank support, a fold-defining member, a plurality of independent infolders, means for producing movements of said infolders whereby edges of the blank are folded upon edge portions of the fold-defining member and the infolders subsequently withdrawn from their operative positions, means for withdrawing said fold-defining member from the folded edge of the blank, a presser member and operative means for applying through said presser member a creasing pressure upon the folds of the blank subsequently to the withdrawal of said infolders and said fold-defining member but before the blank is removed from the position occupied during the folding operation.
15. A folding machine comprising a blank support, a fold-defining member comprising a plurality of co-operating fold-defining parts, a plurality of independent infolders, means for producing movements of said infolders whereby edges of the blank may be folded upon edge portions of the fold-defining member and the infolders subsequently withdrawn, means for withdrawing said fold-defining member by contracting the parts thereof from the folded edges of the blank, a presser member and operative means for applying through said presser member a creasing pressure upon the folds of the blank subsequently to the withdrawal of said infolders and said fold-defining member but before the blank is removed from the position occupied during the folding operation.
16. In a machine for folding cuff blanks or analogous articles, the combination of a blank support substantially stationary relatively to the machine frame, a fold-defining member fitted with movable fold-defining parts whereby it may be contracted and expanded, the fold-defining edges thereof

- adapted to bear directly upon the blanks upon said support, independent infolders, means for producing inward and outward movements of said infolders whereby edge 5 portions of blanks may be folded over edge portions of the said fold-defining member and the infolders subsequently withdrawn from such folds, a presser member, and operative means for producing through said 10 presser member a creasing pressure upon the folds of the blanks, comprising a part movable toward and from the blanks and connections therefor whereby the creasing pressure may be applied subsequently to the 15 contraction of the fold-defining member, and subsequently to the withdrawal of said infolders but before the blanks are removed from the position occupied during the folding 20 operation.
17. In a machine for folding cuff blanks or analogous articles, the combination of a blank support substantially stationary relatively to the machine frame, a fold-defining member fitted with movable fold-defining 25 parts whereby it may be contracted and expanded, the fold-defining edges thereof adapted to bear directly upon the blanks upon said support, a positioning arm for said fold-defining member, independent infolders, means for producing inward and 30 outward movements of said infolders whereby edge portions of blanks may be folded over edge portions of the said fold-defining member and the infolders subsequently withdrawn 35 from such folds, a presser member and operative means for producing through said presser member a creasing pressure upon the folds of the blanks, comprising a part movable toward and from the blanks 40 and a positioning arm and connections therefor whereby the creasing pressure may be applied subsequently to the contraction of the fold-defining member, and subsequently to the withdrawal of said infolders but before the blanks are removed from the position 45 occupied during the folding operation.
18. A folding machine comprising in combination a blank support, a templet for defining the folds of the blanks, on said support, infolders for folding edges of the blanks over edges of the templet, and the following pressing means adapted to come into play after templet and infolders have completed their functions, namely: a presser- 50 actuating member and a presser, the two normally unconnected, and mechanical parts adapted to automatically connect the two during pressing operation, whereby movement in said presser-actuating member is 55 communicated through the presser to the folds.
19. A folding machine having in combination a blank support, a fold-defining member, infolders, a presser, and a pressure producing treadle or the like for producing 60
- pressing movements of said presser, the said treadle and presser being normally disengaged, and intermediate mechanical connections whereby when the treadle is operated it becomes automatically connected with 65 said presser, whereby the pressure upon the treadle is communicated through the presser to the folds of the blanks.
20. A folding machine having in combination a blank support, a fold-defining member, infolders, a presser, and a pressure producing treadle or the like for producing 70 pressing movements of said presser, the said treadle and presser being normally disengaged, and intermediate mechanical connections whereby when the treadle is operated it becomes automatically connected with 75 said presser, whereby the pressure upon the treadle is communicated through the presser to the folds of the blanks and automatically disconnected after the pressing 80 operation is completed.
21. In a machine for folding cuff blanks or analogous articles, the combination of a substantially stationary bed for supporting 85 the blanks to be folded, an expanding and contracting member for defining the folds of the blanks, positioning mechanism for said fold-defining member, whereby edge portions of the latter may be brought into direct contact with the blanks before the folding 90 operation, infolding mechanism constructed and fitted for folding edge portions of the blanks over edge portions of the fold-defining member and for being withdrawn 95 after such folding, means for withdrawing the edge portions of the fold-defining member by contracting them out from the folded edges of the blanks, a member adapted to co-operate directly with the bed for pressing 100 the folds of the blanks after both the infolding mechanism and fold-defining member are withdrawn, mechanical connections for 105 said fold pressing member, whereby it may be accurately positioned upon and removed 110 from the folds of the blanks, and a power lever having disengageable power-multiplying connections with said fold pressing member, whereby the latter is normally disengaged from said lever, but capable of 115 engagement therewith during the pressing operation, so that normally said member may be free to move a substantial extent, and yet high pressure obtained for the pressing 120 operation.
22. In a machine for folding cuff blanks or analogous articles, the combination of a substantially stationary bed for supporting the blanks to be folded, an expanding and contracting member for defining the folds of 125 the blanks, positioning mechanism for said fold-defining member, whereby edge portions of the latter may be brought into direct contact with the blanks before the folding operation, infolding mechanism constructed 130

and fitted for folding edge portions of the blanks over edge portions of the fold-defining member and for being withdrawn after such folding, means for withdrawing the 5 edge portions of the fold-defining member by contracting them out from the folded edges of the blanks, a presser adapted to co-operate directly with the bed for pressing the folds of the blanks after both the infolding mechanism and fold-defining member 10 are withdrawn, mechanical connections for said fold pressing member, whereby it may be accurately positioned upon and removed from the folds of the blanks, and a power 15 lever having disengaging and engaging power-multiplying connections with said presser whereby the presser and lever are normally disengaged but automatically engaged during the fold pressing operation, so 20 that high creasing pressure may be obtained during the pressing operation and extended presser movement normally obtained.

23. In a machine for folding cuff blanks or analogous articles, the combination of a 25 substantially stationary blank support that may be maintained in heated condition, a templet positioning arm, an expanding and contracting templet connected with said arm and having expanding and contracting edges 30 adapted to bear directly upon the unfolded blanks upon said support, infolders fitted to be moved inwardly to fold edges of the blanks over templet edges, and outwardly 35 therefrom, a presser positioning arm, a presser connected therewith constructed to co-operate with the heated bed for creasing the folds of the blanks after the templet is contracted and the infolders moved outwardly, and mechanism co-operating with 40 said presser for producing a creasing pressure, said mechanism comprising a power lever and automatically connecting devices, whereby the presser is normally free for a substantial extent of swinging movement, 45 but becomes connected to the lever when the latter is operated to effect pressing of the folds.

24. In a machine for folding cuff blanks or analogous articles, the combination of a 50 fixed and heated bed upon which blanks may be placed to be infolded, a templet with

a positioning arm, whereby it may be accurately lowered upon and removed upward from the blanks on said support, said templet having expanding and contracting 55 plates, a plurality of independent infolders fitted to move inwardly and outwardly, a presser with a positioning arm therefor, both of the aforesaid positioning arms pivoted at the side of the machine furthest from the operator, whereby when said templet and presser are off the blanks, the blanks are 60 easily accessible to the operator, a power lever, and a contrivance for connecting said lever with said presser during the pressing 65 operation.

25. In a folding machine, a support having a constant location relatively to the general location of the infolders, said support for holding the blanks during the infolding 70 and pressing operations thereon, a fold-defining member, mechanical means for accurately positioning said defining member upon the blanks upon said support, infolders having outward and inward positions, mechanical means for effecting inward and outward movements of said infolders whereby edges of the blanks on said support may be folded over edges of said defining member and whereby said infolders are subsequently moved outwardly from the folded 80 blank edges prior to the pressing operation, said infolders in their outward position inclosing a space within which the presser may pass; a presser adapted to pass within the 85 infolders after the latter are moved outwards and to come upon the folds of the blanks for producing a creasing pressure upon the folds of the blanks while the latter still remain in the same place occupied by 90 them during the folding operation, and mechanical means capable of so applying the presser to the folds for the purpose stated and immediately after or as said infolders moving outwards, leave said folds. 95

In testimony whereof I have signed this specification in the presence of two subscribing witnesses.

GARRY J. DORMANDY.
